UNITED STATES PATENT OFFICE.

CHARLES DAVEY TREGONING, OF GRASS VALLEY, CALIFORNIA.

DOUBLE-ACTING GRINDING PAN-MILL AND AMALGAMATOR.

1,186,709.

Specification of Letters Patent. Patented June 13, 1916.

Application filed October 28, 1915. Serial No. 58,417.

To all whom it may concern:

Be it known that I, CHARLES D. TREGONING, a citizen of the United States, residing at Grass Valley, in the county of Nevada 5 and State of California, have invented certain new and useful Improvements in Double-Acting Grinding Pan-Mills and Amalgamators; and I do declare the following to be a full, clear, and exact description of the 10 invention, such as will enable others skilled in the art to which it appertains to make and use the same.

This invention relates to ore pulverizing machines and more particularly to what are 15 known as pan mills.

The object of the invention is to provide a machine of this character which while simple in construction will efficaciously re-

grind coarse sand to any desired fineness. 20 Another object is to provide a machine of this character constructed to prevent wear on the intermeshing gear wheels employed for grinding and which is equipped with improved means for holding the gears in oper- 25 ative position.

Still another object is to provide improved driving means for a machine of this character so arranged as to prevent oil or grease from dropping into the mill.

With these and other objects in view, the 30 invention consists of certain novel features of construction, and the combination and arrangement of parts as will be hereinafter more fully described and claimed.

In the accompanying drawings: Figure 1 35 represents a vertical section of a mill constructed in accordance with this invention; Fig. 2 is a horizontal section thereof taken on the line 2—2 of Fig. 1; Fig. 3 is a horizontal section taken on the line 3—3 of Fig. 40 1; Fig. 4 is a detail vertical section taken on the line 4—4 of Fig. 2. Fig. 5 is a detail side elevation of one of the disks and the gear carried thereby shown in section; Fig. 45 6 is a top plan view of the disks; Fig. 7 is a bottom plan view thereof.

In the embodiment illustrated a supporting base 1 is shown having a frame 2 disposed thereabove and supported by uprights 3 rising from said base 1. A grinding pan 5 is mounted on the frame 2 and secured thereto by any suitable means. As shown this pan 5 has a reduced cylindrical lower portion 6 in which are mounted a bed plate 7 and a plurality of grinding disks 8, the combined thickness of the grinding disks and

the bed plate substantially filling this reduced portion 6 of the pan, as is shown clearly in Fig. 1. The reduced portion 6 of the pan connects with the larger upper portion thereof by an inclined seat or wall 9 on which rests an annular internally toothed ring 10 which is designed for engaging the teeth of a plurality of gears 11 which are carried by the disks 8 each of said disks having an upstanding angular standard 12 at its center which projects through each gear 11 carried thereby and thus holds the gears and disks in assembled relation so that they will turn together on revolving of the gears. 70 Five of these gears are herein shown, one being arranged centrally and indicated at 11' and with which the other four gears mesh and receive rotary motion therefrom. This central gear 11' has a central opening 75 through which projects an upright driving shaft 13 which is mounted at one end in a suitable bearing 14 secured to the base plate 1 and at its other end in the cross bar 15 of an inverted U-shaped brace which is connected at its opposite ends to the opposite sides of the pan 5 and is herein shown bolted thereto. This central gear 11' has an upwardly extending tubular sleeve 16 provided with a clutch member 17 which is designed 80 to be engaged by a co-operating clutch member 18 keyed to the shaft 13 and by means of which rotary motion is imparted to the central gear 11'. This upright driving shaft 13 as herein shown is driven by means of a horizontally disposed shaft 19 on which is mounted a beveled gear 20 which meshes with a similar shaped gear 21 carried by the shaft 13. This shaft 19 is provided with 85 pulleys 22 over which a driving belt (not shown) is designed to pass for imparting motion to the shaft 19 and hence through said beveled gears 20 and 21 to the shaft 13 whereby the gears within the pan are 90 revolved.

As shown the pan 5 is made cylindrical to contain the ore and gears and is provided at one side with a spout or opening 24 through which the ore and water are drawn after the ore is pulverized. The mouth of the spout 24 is provided with a gate or slide valve 25 the height of which controls the overflow of the water and ore from the pan, it being of course understood that the height of this gate may be varied to suit the wishes of the operator.

The bed plate 7 is preferably provided

with a plurality of grooves 7' similar to those of a mill-stone and the disks 8 are similarly provided on their lower faces with grooves 8' four of which are herein shown arranged at diametrically opposite points although it is to be understood that any desired number may be employed and they may be arranged in any desired or suitable manner.

- 10 From the above description it will be obvious that the central gear 11' when clutched to the shaft 13 will be rotated by said shaft and the other gears 11 which mesh with the central gear will be rotated by said central gear and turned in a direction opposite to that in which the central gear turns. These gears 11 are kept in proper alinement by the teeth of the ring 10 which mesh with the gears 11. The gears are thus prevented from 15 being worn and when the machine is in operation they will revolve upon their own axes and also around the central gear thereby producing a very efficient pulverizing effect on the material to be ground which is disposed between the lower faces of the disks 8 and the upper face of the bed plate 7.

The partially crushed ore and water may be introduced into the pan through any suitable means not shown.

- 20 When it is desired to clean the machine, the loose gears are removed together with the disks on which they are mounted, the sliding gate valve 25 is raised and the powdered ore scraped out through the 25 spout 24.

While five gears are shown in the accompanying drawings as being a convenient number it is not desired to limit the invention to that number as any number may be employed that may be found useful.

- 30 The bed plate 7 is shown provided at diametrically opposite points with radially extending apertured ears 7" which are designed to receive fastening elements for securing the plate to the bottom of the pan.

45 As shown the bottom of the pan 5 has a central opening therein for the passage of the shaft 13 and said opening is surrounded by an upstanding sleeve 5^a which may be of any suitable or desired height being here shown extending above the top of the central gear which is mounted on said sleeve.

50 It will thus be understood that by providing or mounting each of the gears 11 on an individual driving disk 8 wear on these gears will be prevented, the wearing effect taking place between the upper face of the bed plate 7 and the lower face of these disks and when the disks become worn so as to render 60 them unfit for use they may be quickly and readily removed and others substituted in

their places thereby greatly economizing in the structure of the mill as the gears are much more expensive to manufacture and replace than are the disks 8 and hence the 65 gears themselves will be used as drivers for the disks and not as grinders. Moreover by so mounting the shaft 13 and the driving mechanism shaft below the pan 5 all grease and oil is prevented from dropping into the pan as 70 ordinarily occurs when the shaft driving mechanism is located above the pan.

I claim as my invention:

1. In an ore pulverizing machine the combination of an ore receiving pan, a bed plate 75 mounted in the bottom thereof, grinding disks mounted to revolve flatwise on said bed plate, a central gear arranged therein, a plurality of gears mounted on and fixed to said disks and surrounding and meshing 80 with said central gear, and means for rotating said central gear.

2. In an ore pulverizing machine the combination of an ore receiving pan, a bed plate mounted in the bottom thereof, grinding 85 disks mounted to revolve flatwise on said bed plate, a central gear arranged therein, a plurality of gears mounted on and detachably engaged with said disks, means for maintaining said gears in operative position, 90 and means for rotating said central gear.

3. In an ore pulverizing machine the combination of an ore receiving pan, a bed plate mounted in the bottom thereof, grinding disks mounted to revolve flatwise on said 95 bed plate, a central gear arranged therein, a plurality of gears mounted on and detachably engaged with said disks, means for maintaining said gears in operative position, and means extending through the bottom 100 of the pan for rotating said central gear.

4. In an ore pulverizing machine the combination of an ore receiving pan, a bed plate mounted in the bottom thereof, grinding disks mounted to revolve flatwise 105 on said bed plate, a central gear arranged therein, a plurality of gears mounted on and detachably engaged with said disks, means for maintaining said gears in operative position, a driven shaft extending upwardly through the bottom of said pan and through said central gear, and coöperating clutch members on said shaft and gear for connecting them.

In testimony whereof I have hereunto set 115 my hand in presence of two subscribing witnesses.

CHARLES DAVEY TREGONING.
